LESLIE O. PARKER AND LEO C. SHIPPY, OF ANDERSON, INDIANA, ASSIGNEES TO DELCO-REMY CORPORATION, OF DAYTON, OHIO, A CORPORATION OF DELAWARE.

ELECTRIC LAMP.

Application filed February 12, 1927. Serial No. 167,831.

This invention relates to improvements in lamps and particularly the type of lamp used on motor vehicles and the like.

It is among the objects of the present invention to provide means for securely fastening the glass panel or lens of the lamp to the lamp body, said means being of simple structure and design and adapted to prevent loosening of the lens through vibration.

Further objects and advantages of the present invention will be apparent from the following description, reference being had to the accompanying drawing, wherein a preferred embodiment of one form of the present invention is clearly shown.

In the drawing:

Fig. 1 is a view of the lamp in side elevation, a portion thereof being broken away to show the cross sectional construction;

Fig. 2 is a front elevation of the expandible ring;

Fig. 3 is a view of the lens rim.

Referring to the drawing, the numeral 20 designates the lamp body shown in the form of a paraboloid, said body being provided with a suitable lamp socket 21 for receiving an electric lamp bulb 22. The outer edge of the lamp body is provided with an inwardly extending flange 23.

The lens is designated by the numeral 24. A split rim 25, made up of any suitable resilient material so that the ring is expandible, surrounds the lens. The front edge of the rim 25 is provided with an inwardly extending annular flange 26, while the other or rear edge has a laterally extending flange 27, provided with an inwardly extending edge 27^a. An annular groove 28 is formed in the peripheral surface of the rim between the flanges 26 and 27, said groove being adapted to receive the inwardly extending flange 23 of the lamp body 20. The lens 24 fits in the rim 25, the front surface 45 adjacent the edge of the lens engaging with the edge of the flange 26.

An expandible member 29 is provided in the rim 25, said member having an annular flange which rests in the seat provided by the flange 27 and its inwardly extending edge 27^a, formed on said rim. This expand-

sible member is in the form of a split ring and is made up of a material more resilient than the rim, so that it will exert an outward pressure on the flange 27 of the rim, thereby aiding in expanding said rim into locking engagement with the lamp body flange 23.

In the foregoing it may be seen that an inexpensive mounting means is provided for the lens of the lamp, which may vary considerably in diameter and thickness without necessitating alterations in the mounting means, said mounting means being of a resilient expandible character, thereby tending to eliminate the loosening up of the lens and consequent rattling.

While the form of embodiment of the present invention as herein disclosed, constitutes a preferred form, it is to be understood that other forms might be adopted, all coming within the scope of the claims which follow.

What is claimed is as follows:

1. A lamp, comprising in combination, a lamp body; a lens; an expandible rim for said lens; and an expandible ring in said rim for retaining the lens therein and for expanding the rim into gripping engagement with the lamp body.

2. A lamp, comprising in combination, a lamp body; a lens; a split, expandible rim for said lens, said rim having a portion extending into the lamp body; and an expandible ring in said rim for holding the lens therein and for assisting the expandible rim tightly to grip the lamp body.

3. A lamp, comprising in combination, a lamp body having an inwardly extending annular flange; an expandible rim for said lens, the rim having an annular groove adapted to receive the flange of the lamp body; and an expandible ring in said rim for holding the lens in the rim, and for expanding the rim to cause proper engagement between the rim groove and lamp body flange, whereby the rim is securely held on the said lamp body.

4. A lamp, comprising in combination, a lamp body having an annular, inwardly extending flange; a lens; an expandible rim for said lens, provided with annular, inwardly extending flanges, one of which is

engaged by the lens, said rim having an annular groove formed in its outer peripheral surface, between the flanges, said groove being adapted to receive the lamp body flange; and an annular expandible member in the rim engaging the lens and the other rim flange for holding the lens in

the rim and expanding the rim into locking engagement with the flange of the lamp body.

In testimony whereof we hereto affix our signatures.

LESLIE O. PARKER.
LEO C. SHIPPY.
